[57] CLAIM

The ornamental design of an intumescent seal, as shown and described.

DESCRIPTION

FIG. 1 is a perspective view of the intumescent seal of the present invention;

FIG. 2 is a front elevational view thereof;

FIG. 3 is a left side elevational view thereof;

FIG. 4 is a back elevational view thereof;

FIG. 5 is a right side elevational view thereof;

FIG. 6 is a top plan view thereof; and,

FIG. 7 is a bottom plan view thereof.

The intumescent seal is broken on the ends to indicate indefinite length.
